(57) **CLAIM**

We claim the ornamental design for an ergonomic syringe adapter, as shown and described.

DESCRIPTION

FIG. 1 is a perspective view of the ergonomic syringe adapter, showing our new design;

FIG. 2 is a right side elevational view thereof, said left side elevational view being a mirror image thereof;

FIG. 3 is a rear end elevational view thereof;

FIG. 4 is a front end elevational view thereof; and,

FIG. 5 is a top plan view thereof, said bottom plan view being a mirror image thereof.

The broken lines showing in FIG. 4 is to illustrate portions of the article and form no part of the claimed design.
